UNITED STATES PATENT OFFICE.

THOMAS K. KEITH, OF BOSTON, MASSACHUSETTS, ASSIGNOR, BY MESNE ASSIGNMENTS,
TO UNITED SHOE MACHINERY COMPANY, OF PATERSON, NEW JERSEY, A CORPO-
RATION OF NEW JERSEY.

LASTING-MACHINE.

1,030,820.

Specification of Letters Patent. Patented June 25, 1912.

Application filed April 24, 1897. Serial No. 633,693.

To all whom it may concern:

Be it known that I, THOMAS K. KEITH, of Boston, county of Suffolk, State of Massachusetts, have invented an Improvement 5 in Lasting-Machines, of which the following description, in connection with the accompanying drawings, is a specification, like letters on the drawings representing like parts.

10 This invention relates to machines for use in the manufacture of boots and shoes and is herein shown as embodied in a machine for lasting shoes.

An object of the invention is to provide 15 a machine with the aid of which the manufacture of shoes can be carried on more rapidly than with prior machines and, partly with the same object in view, to reduce the labor by making the machine to perform 20 automatically certain portions of the work now generally requiring more or less special attention and labor from the operator.

Important features of this invention consist in means for lasting the heel and toe 25 of a shoe while the shoe occupies one position, means for lasting the sides with the shoe in a different position, and a shoe support movable with the shoe from one to the other position; toe and heel lasting mechanisms which are separable to permit the introduction and removal of a shoe and a shoe 30 support which is movable with a shoe thereon into and out of position between said end lasting mechanisms; an end lasting mechanism which is movable downwardly to press 35 and flatten the overwiped upper hard down upon the last bottom and which is automatically advanced farther over the shoe as it is moved downwardly; the provision of 40 a movable carrier having a plurality of shoe supports and mounted, with relation to end lasting mechanisms and to automatic or other side lasting mechanism, for movement to carry a shoe away from the end lasting 45 mechanisms and to present that shoe to the action of the side lasting mechanism while presenting a second support in place between the vacated end lasting mechanisms by which another shoe shall be operated upon; 50 the provision of a side lasting device, which may be a wiper that can be used all around the shoe, or a fastening mechanism, or both a lasting device and a fastening mechanism, and mechanism for operating the same and 55 giving thereto traveling movements to act

on different portions of the shoe successively; the provision of mechanism for giving to a shoe support rotative movements while the toe and heel are being operated upon in combination with means to suspend 60 such movements during operation on the sides of the shoe by traveling lasting means or fastening means; the provision of means to reverse, while the shoe is being turned at the heel or toe, the direction in which a lasting 65 or fastening mechanism has moved while operating on a side of the shoe whereby said mechanism is carried back to its starting position for side lasting; the provision that a device with a lasting or beating 70 function is advanced under downward pressure and caused to treat the upper by impact when or after it reaches the edge of the shoe; the provision that a lasting or fastening device is actuated automatically in a 75 closed path in which it slides forwardly over the upper, and then rises and retreats to avoid drag on the upper during its return movement.

The foregoing and other features of the 80 invention, the importance of which is not to be considered as prejudiced by the fact that they are not here specifically mentioned, together with certain details of construction and combinations of parts will appear in 85 connection with the following description of the machine which is illustrated for exemplification of the invention, and will then be particularly pointed out in the claims, reference being had also to divisional applications 589,681 and 639,979 in which are to 90 be found the claims to the automatically operated tacker with its attached upper wiping foot and the claims to the end lasting mechanism *per se*, as distinguished from the 95 combination claims comprised in this application.

Figure 1, in perspective, shows a lasting machine embodying my invention in one form, the arms d^4 carrying the side clamps 5 100 being partially broken away, and the receptacle for discharged tacks being omitted. Fig. 2 is a side elevation somewhat in perspective. Fig. 2^a is a detail showing the yoke and part of the arm employed to sustain the tacker bed. Fig. 3 is a top or plan view of the machine shown in Fig. 2. Fig. 4 is a detail showing the cam for actuating the pawl controller. Fig. 5 is a detail side view of the tacker mechanism. Fig. 6 is a sec- 110

tional detail in the line x , Fig. 5. Fig. 7 is a detail showing part of the movable carrier and means coöperating with the jack spindle to lock the carrier temporarily in place. Fig. 8 is a sectional view of the tacker head. Fig. 9 shows in detail a lever for swinging the tacker. Fig. 10 is an enlarged sectional detail in the line $x'-x'$, Fig. 8. Fig. 11 is a detail of the ball bearing for the movable carrier. Fig. 12 is a detail showing the base plate of the jack which carries the lasting devices. Fig. 13 is a detail of the plate which supports and directs the wipers or slides of the lasting device. Fig. 14 is a detail of the stopping and starting mechanism. Fig. 15 is an enlarged detail chiefly to show the toe and heel pads and the toe rest. Fig. 16 is a detail chiefly to show the lever for operating the pawl lever g^7 . Fig. 17 is a detail showing the lower end of the raceway for the tacks, the pick-off and part of the tacker head. Fig. 18 is an enlarged sectional detail of the toe-lasting devices, the section being taken longitudinally through the arm s^8 , the studs 70 and 71 and coöperating parts; and Fig. 19 shows one of the slides s^2 detached to show its two holes.

The framework shown consists chiefly of a base A having two fixed posts or columns A' , A^2 , and standards A^3 , A^4 . The standards A^3 carry bearings for the main shaft A^5 , and the standards A^4 , bearings for the auxiliary shaft F'. The post A' has secured to its upper end by bolts B a plate B'. The post A' also supports brackets B² which have bearings for a rock-shaft B³ provided with an upwardly extended arm B⁴ having at its upper end a hole in which enters loosely a stud B⁵, carried by a yoke B⁶, see Fig. 2^a, the ears of said yoke supporting a stud B⁷ that passes through ears at the lower side of the tacker bed B⁸.

The tacker bed carries upon its upper side standards B⁹ and B¹⁰. The standards B⁹ have bearings for the tacker actuating shaft C, provided at one end with a sprocket wheel C' over which is extended a sprocket chain C², said chain embracing a sprocket wheel C³, mounted on a stud C⁴ and having an attached sprocket wheel C⁵ over which is extended a sprocket chain C⁶, driven from a sprocket wheel C⁷, fast on the main shaft, said shaft C having cams C⁸, C⁹ and C¹⁰. The standard B¹⁰ has a stud D on which are mounted three levers D', D², D³, see Fig. 3.

The lever D', actuated by the cam C⁸, is designated as the driver lever; it raises the driver D⁴ in the tacker head D⁵, through the links D⁶, D⁸ and lever D⁷, the lever D⁷ being mounted on a swinging link D⁹, pivoted at a, see Fig. 2; a spring D¹⁰, connected with the lever D⁷ and with a stud a' fast on the link D⁹, serves to depress the driver bar quickly whenever the roller stud a² on the

driver lever arrives at the abrupt end of the cam C⁸. The driver bar has a driver a³ guided in the nose a⁴ of the tacker head. This nose, see Figs. 8 and 10, has two spring-pressed pins a⁵ provided at their contiguous ends each with a groove, the grooves together forming a pocket to receive and sustain the head of a tack while the driver is elevated. The driver in its descent strikes the head of the tack and drives it from between the pins out through the nose into the stock, the pins at such time yielding under the action of the springs a⁶ and permitting the driver to pass between said pins. The upper end of the link D⁶, referred to, is entered by a stud a⁷, see Fig. 2, which extends from a collar a⁸ fastened to the upper end of the driver bar by a set screw a⁹, see Figs. 3 and 8.

The driver-bar, see Fig. 8, has secured thereto, by a set screw a¹⁰, a collar b having a projecting pin b', that enters an irregular slot b² in a pick-off lever b³, pivoted at b⁴, the lower end b⁵ of said lever, located at the end of the raceway b⁶, see Fig. 17, having an open notch 2, the walls surrounding said notch receiving and supporting the head of the endmost tack of those coming down the raceway b⁶, the movement of said lever b³ in the direction of the arrow Fig. 17, causing it to take the tack in its notch, carry the same laterally and put its pointed end within the open end of a tack guide b⁸, said tack guide leading the tack into the tacker head, the head of the tack resting in the pick-off tack pocket formed by the grooved ends of pins a⁵, the driver bar being then lifted.

The tacks to be driven are supplied to a feeding bin b⁹ and are led thence through a tube b¹⁰ to a hopper b⁷ from which they pass to the raceway b⁶. Those tacks which arrive in the hopper with their points properly directed downwardly enter the slot in the upper end of the raceway, while those tacks which enter the hopper head first fall below the receiving end of the raceway and drop on the top of an inclined bar c, and slide down said bar into a basin or receptacle c', see Fig. 5, from which they are returned from time to time into the bin b⁹. The lever b³ derives its movements by the rising and falling of the driver bar.

The tube b¹⁰, see Fig. 6, is slotted near its lower end at 3 to let the tacks sliding down said tube drop therefrom and enter the hopper. The tacks are permitted to escape from this tube only at intervals, the tube having a gate c², which enters a vertical slot cross-wise of the tube, as best shown in Fig. 6, said gate being normally closed by a suitable spring c³ connected at one end to said gate, and at its other end to a suitable pin c⁴. The gate c² is opened at intervals by a gate opener c⁵, shown as a finger pivotally

mounted on one end of the stud a , before described, held in a forward projection of the tacker bed B^8 . The gate opener has near its upper end a slot, see Fig. 5, which receives 5 a pin c^6 extended from the side of the hopper, said pin tending to keep the gate opener in proper working position, but permitting the hopper to rise and fall as the tacker is put into and out of operative position as 10 required.

The tacker head has a backwardly extended arm E sustained on a stud E' at the upper end of link D^9 , said arm being turned about said stud by means of lever D^3 having 15 at its inner end an attached arm d , see Fig. 3, provided at one end with a slot which receives a stud d' extended from the side of arm E . The tacker head is moved laterally by swinging the link D^9 through lever D^2 , 20 see Fig. 3, having at its inner end a pin d^2 that enters a slot at one end of an arm d^3 fastened to said link. The levers D^2 and D^3 move the tacker head forward and lower the same into position so that the driver bar 25 may be operated to drive tacks into the edge of an upper laid over upon the inner sole by the lasting devices and clamped in position to receive tacks, and move said tacker head backwardly out of operative position after 30 the tack has been driven. While the tacking means is operating to drive tacks automatically about the shoe to confine the upper to the inner sole, the operator will be devoting his time to removing from the jack 35 the lasted shoe previously tacked, and to putting another last having a shoe upper thereon in place and preparing the same to be tacked after the jack has been moved and the prepared shoe brought into operative 40 relation to the tacking means.

The tacker head, see Fig. 5, has a forwardly extended edge gage or feeler E^2 against which bears and moves the flanged guiding edges of the side clamps 5, and the 45 guiding flanges 6 and 7 of the toe and heel clamps f , f' . The tacker head has an upper wiping foot or member E^4 , which, when the said head is being put into working position, is adapted to strike the said clamps and 50 sliding thereon let the head come gradually into working position. The flanged edges of the side clamps are carried by two arms d^4 , mounted loosely on a rod d^5 , mounted in ears d^6 , of a revolving base plate d^7 , said 55 arms having each a finger d^6 , the arms at opposite sides of the base plate being connected by suitable springs d^8 . Upon the rods d^5 are also mounted two pairs of levers e one pair at each side of the last. These 60 levers are best shown in Fig. 1 where the levers d^4 referred to are represented as broken off. Suitable springs e' act on the short arms of the levers e and normally keep the opposite ends thereof, which are prefer- 65 ably provided with friction surfaces or pads

e^2 , pressed against the upper at the sides of the last near the bottom thereof. The levers e at opposite sides of the last are united by links 10 with actuating levers e^3 so that by raising the free ends of said actuating levers 70 said two sets of levers may be moved away from the last, and as said levers are so moved they act on the fingers d^6 , see Fig. 2, of the arms d^4 , and carry said arms and the side clamps 5 away from the upper on the 75 last.

The heel and toe clamps f , f' , herein shown as composed of metallic straps hinged together centrally, see Figs. 1 and 3, have respectively at their upper ends guiding 80 flanges 6, 7, shaped to conform to the shape of the last at the junction of its sides and bottom about the heel and toe ends thereof. The ends of these heel and toe clamps have studs on which are fitted the ends of like 85 links f^2 , each jointed at its opposite end to the upper end of an arm or lever f^3 , said arms being each mounted loosely on rods f^4 , held in ears f^{14} , so as to be turned about said pivots when the toe and heel clamps are to 90 be removed from contact with the heel and toe of the shoe. This removal of the heel and toe clamp is effected simultaneously by means of a link f^{4x} , f^{5x} , the part f^{4x} being made as a yoke, and the part f^{5x} being 95 threaded, see Fig. 15, to receive a nut f^6 , the shank of the said nut acting against a cross-bar f^7 uniting the two like links f^3 at that end of the machine.

The machine is provided with two similar 100 base plates d^7 each sustaining similar side clamps and heel and toe clamps. Each base plate has attached thereto a ratchet wheel g , but as these are alike, I need herein specifically describe but one of them. Each of 105 these ratchet wheels has a hub or spindle g' , which is extended through a suitable hole in a pivotally mounted carrier g^2 , on the column A^2 , said column having at its upper end a stud g^3 , see Fig. 11 that enters a hole 110 in the underside of said carrier g^2 , balls or rolls g^4 being applied between the top of said post and the underside of said carrier to constitute a ball bearing. These base plates are rotated while the tacker is working to drive tacks in the upper about the heel and toe thereof and while the upper along the sides of the last is being tacked to the inner sole, the foot plates remain at rest and the tacker head is moved longitudinally 115 with relation to the stationary last, as will be described. The teeth of the ratchet wheels g are engaged while the jack is being rotated, by a pawl g^5 , pivoted at g^6 on the short arm of a lever g^7 pivoted at 12, one 120 end of said pawl being acted upon by a spring 13, connected at one end to said lever g^7 . While the pawl is acting to turn the base plate and the last during the insertion 125 of tacks about the toe and heel of the upper, 130

the end of the pawl is permitted to engage the teeth of the ratchet wheel, said pawl acting intermittently to impart to said ratchet wheel a partial rotation, the lever g^7 , during such operation, being struck, after the driving of each tack, by the upper end of a lever g^8 , see Fig. 1, mounted on a stud g^9 , fixed to the post A^2 , said lever g^8 being acted upon by a cam g^{10} on the main shaft, a spring g^{12} serving to keep the end of said lever against said cam. This lever acts continually, and it will move either one of the two like levers g^7 whichever may be brought by the movement of the carrier g^2 , into its range of movement, but when the edge of the upper along the side of the last is to be tacked, and the ratchet wheel on the base plate is to stand still while some tacks are driven, then the effective motion of the pawl 20 is stopped by or through a pawl controller h , shown as a lever pivoted at h' , one end of the said pawl controller being at such time acted upon by a cam h^2 , see Figs. 3 and 4, fast to a ratchet wheel h^3 , turning on a stud screw 14, screwed into a threaded hole 15, see Fig. 11, in the stud g^3 . The ratchet wheel h^3 will have in practice a tooth for each tack to be driven in going completely about a shoe, and the number of its teeth 25 corresponds with the number of teeth of the ratchet wheel h^4 to be described. The ratchet wheel h^3 is moved one tooth at a time by the pawl 16 carried by the lever g^7 . When the projections of the cam h^2 act 30 to move the cam controllers said controllers are moved outwardly so that they operate on and put the acting ear of the pawl g^5 out of position with relation to the teeth of the ratchet wheel g . Each lever g^7 is moved on its back stroke by a suitable spring g^{12} . Each hub or spindle g' is provided below the carrier g^2 with a collar 17 on which rests a friction device 18, shown as a spring, and the lower end of said hub has a recess see 35 Fig. 7, in which may enter a locking device 19, shown as a bolt attached to a lever m , pivoted at m' on a slotted cross bar m^2 , supported by the post A^2 , an arm of said lever having connected to it a rod m^3 having an 40 adjustable nut or stop m^4 , said stop being so located that when the treadle m^5 is depressed by the foot of the operator the said rod will be drawn down to withdraw the locking device 19 and leave the hub free to 45 allow the carrier g^2 to be turned. The lever m^5 is fixed by a suitable screw 22, on a collar 23 surrounding loosely the main shaft. The spring 24, see Fig. 1, acts normally to raise the lever m so that whenever a hub g' comes 50 in position over the said locking device the latter will be first acted upon by the beveled end of the hub, and then the locking device will enter the recess at the end of the hub. The lever m^5 , Fig. 1, performs a second 55 purpose, that is, it has connected to its in-

ner end a shouldered link m^6 , which, when the operator puts his foot on the said treadle, rises, and acting on the arm m^7 , fast on the rock shaft B^3 , turns said shaft and carries the tacker head backwardly so 70 that the tacker may be carried out of operative position while the carrier g^2 is being rotated partially from one into its other position.

To give to the tacker head its longitudinal 75 reciprocation in one direction while the side edges of the upper are being tacked, and in the opposite direction while the heel and toe of the upper are being tacked, I have provided the tacker bed plate B' with an arm n , 80 see Fig. 3, and to this arm by a stud n' , I connect one end of a link n^2 , the opposite end of said link, being extended across the tacker bed plate and being provided with an adjustable stud n^3 , which enters a slot n^4 , 85 in a lever n^5 , pivoted on the plate B' at n^6 . The opposite or free end of the lever n^5 , has mounted on it pivotally a block n^7 , see Figs. 3 and 9, to which by a pin n^8 is joined one 90 end of a link n^9 , entering a loose block n^{10} , having a shank, see Fig. 9, which enters a hole in the upper end of a lever n^{12} , mounted on a stud n^{13} , in the post A' . The short arm of the lever n^{12} is extended outwardly over an auxiliary lifting device o , pivoted at 26, 95 on a stand 27, the free end of said auxiliary lever having a stud or projection 28 which rests on the periphery of a cam F , fast on the auxiliary shaft F' , said lever being kept in contact with said cam by a spring n^{14} , 100 said shaft carrying the ratchet wheel h^4 , (Fig. 2), which is acted upon by a suitable pawl 29, pivoted on a pawl carrier 30 mounted loosely on the shaft F' , and having connected to it a link 31, attached by a screw 32 to a cross slide 33 made adjustable in a groove of a disk 34 fast on the end of the main shaft.

The ratchet wheel h^4 has a tooth for each nail to be driven, and it is rotated once during the lasting of each shoe, and the cam F , acting on the levers o and n^{12} , and said spring n^{12} causes the lever n^5 to be moved first in one and then in the opposite direction, and in so doing, acting on the link n^2 , 115 moves the tacker head first in one and then in the opposite direction.

The tacking of the upper will be commenced at the shank, see Fig. 3, while the foot plate is held stationary and thereafter the tacker will be made to travel in the direction of the arrow 80 following the contour of the last and shoe, Fig. 3, until the curved part of the toe of the upper of the shoe on the last is in position to be tacked, 120 at which time the rotation of the foot plate will be commenced and at the same time the traveling movement of the tacker bed plate and tacker will be reversed and moved step by step, and will arrive at its starting posi- 125 130

tion as the foot-plate completes a semi-rotation to effect the tacking of the toe. Then while the foot plate is held at rest the tacker bed plate will be again moved in the direction of the arrow 80 to insure the driving of tacks along the other side of the shoe from the toe to the heel, and when the tacker comes to the curved part of the heel the rotation of the foot plate will be again commenced and the bed plate of the tacker will be again started backward on its return movement. The cam F is so shaped as to move the lever n¹² two complete strokes during the lasting of each shoe. The auxiliary shaft F', see Figs. 1 and 14, has at one end a cam p, which acts on a lever p', pivoted at p² on a stand p³, and the opposite or right hand end of said lever has a pivoted detent p⁴ to which is connected a suitable spring 20 36, the spring acting to keep the said link p⁴ against a stop 37, and with the free end of the said link under a projection 38 of a pronged lever 39, pivoted on a collar 40 fast to a slide rod 41 having at its upper end a handle t⁵. The rod, see Fig. 3, has co-acting with it a locking device b^{6x} under the control of a spring b^{6x}.

Viewing Fig. 14, the prong of the lever 39 is shown as acting against and holding the 30 upper end of an elbow lever 42, mounted loosely on the main shaft A⁵, swung to the left in which position the pulley G will be fast on the main shaft A⁵. The opposite end of the elbow lever has a pin or projection 43 which acts against a cam surface 44 on a second lever 45, pivoted at 46, and acted upon by a suitable spring 47, which, when free to act, will turn the said lever over toward the right.

40 The main shaft will be stopped whenever the heel of cam p passes from under the pin at the end of the lever p', which may be obviously depressed by a suitable weight or spring. The movement of the other end of the said lever lifts the pronged lever 39 and frees the elbow lever 42 thus enabling the lever 45 to be turned by the spring 47, to bring its inclined upper end, see Fig. 3, against the end of a latch 48, which is therefore moved to one side and freed from engagement with one of the teeth on the inside face of the hub of the pulley G which is loose on the main shaft A⁵. This clutch pulley is old, but the addition to it of the lever p' to throw it out of operation automatically is, I believe, of my invention, no claim however is made to this invention in the present case.

45 The base plate, see Figs. 12 and 15 has two guides 50 spaced apart to form between them a way in which is located the foot 51 of a toe rest 52, the foot having a pawl 53 to engage one of a series of ratchet teeth 54 to hold the toe rest in any position into 60 which it may be adjusted. The upper end

of the lever g⁸, see Figs. 3 and 16, has fixed on it by a set screw g²⁰, a finger g²¹, on which is pivotally mounted a pawl g²², said pawl being normally held up by a spring g²³, see Fig. 16, against a stop g²⁴ to keep the end of said pawl in position to act against the pawl carrier g⁷, see Fig. 3, and turn said pawl carrier at each movement of said lever g⁸.

When the carrier g² is moved to take a 70 tacked shoe from tacking position, and to place in position the other jack holding a shoe prepared to be tacked, the pawl carrying lever g⁷ for co-operating with the jack being placed into tacking position will meet the upheld pawl g²² and sliding over it will depress said pawl, the spring g²³ enabling the pawl g²² to rise and stand in correct operative position with relation to the pawl carrying lever g⁷. The cross bar m² has 80 near its ends suitable slots r in which are placed like levers r', pivoted at r² to treadles r³, fulcrumed at r⁴, said levers being normally held up by suitable springs r⁵. The upper ends of these levers r' are forked to 85 present ears which receive pins r⁶, said pins entering suitable lugs r⁷ at the undersides of plates r⁸, said plates each having a leg r⁹, adapted to rest on a shoulder or projection r¹⁰ of the lever r', said leg being adjustable 90 vertically on said plate to thereby determine the inclination of said plate to correspond with the bottom of the toe or heel of the last. The top of the plate r⁸ has two like ears 60 carrying a pin 61, which also 100 passes through two ears 62 extended from the lower side of like frames s, so that said frames s, having shoulders 100, see Fig. 1, may tip on said pins about an axis in the line of the direction of the length of the 105 last. These frames s, both alike, have each secured to them by screws w a top plate s', see Fig. 13, provided with slots 65, 66 and 67, and screw receiving slots 69, the front ends of the plates s' being provided with a 110 U-shaped space to conform substantially to the contour of the last at its toe and heel. Under the plates s' and resting on the shoulders 100 are placed the toe and heel lasting slides s², s², made each independent of the 115 other. The lasting slides s², shown partially in Fig. 3 and in Fig. 19 where one slide is represented detached, have each two holes 120, 121, instead of a stud and a curved slot, as heretofore common. Suitable guides 120 79 connected to the plate s' overlap the links s³ and aid in keeping them on the plate s'. After the upper to be lasted has been put on the last, the last will be put on the heel pin t, pivoted on the rod f⁴, and the 125 toe end of the last will be laid on the toe rest. In this condition the heel and toe clamps will be made to fit the heel and toe of the last by turning the nut f⁶, and the inner sole will be laid on the bottom of the 130

last within the edges of the upper, and then the levers e^8 will be turned to let the arms e meet the upper lying against the sides of the last and press said upper close to the last. The movement of the arms e against the last permits the springs d^8 to draw the arms d^4 toward the last and place the guiding flanges of the clamps 5 against the upper along the side edges of the last in line with the guiding flanges 6 and 7 of the toe and heel clamps. The operator now by suitable pincers may engage the edges of the upper and draw them above the inner sole to take out any stretch and fit the upper to the last, and then he will move the levers r' each toward the last in a slot r , and he will cause the U-shaped ends of the plates s' to be carried forward to stand just above the heel and toe clamps. A suitable pawl, as 80^x , carried by each of said levers r' engages the ratchet teeth 81 on the cross bar m^2 and holds the levers r' in their adjusted positions. This having been done the operator engages first one and then the other of the like levers 77 , and moves the slides s^2 forward into the position shown in Fig. 3, said slides having given to them, due to the shape of the slots 65 and 66 in which the pins 70 and 71 travel, a combined forward and inward movement so that they will act on the edge of the upper and by pressure thereon in radial lines from the center of the circle of the heel and toe will lay the said edges snugly over the inner sole.

The slides and their actuating mechanism constitute what may be designated as the lasting devices, and they having been moved to lay the edges of the upper over on the inner sole and press the same in place, the operator withdraws the slides and then raises the pawls 80^x and turns the levers r' to throw them apart leaving the shoe on the jack with its upper held at sides and toe and heel by the side and toe and heel clamps. The jack may now be moved into position under the tacking head to have the upper tacked in place.

In this machine two operations can go on simultaneously, viz:—tacking and preparing for tacking. The tacker head is held in working position against the face of the guide 7 by the action of a weight t^3 and cord t^4 . It being desired to start the machine in operation, the main shaft being at rest, the operator will engage the locking device t^{5x} , turn the same from its engagement with the rod 41 , and thereafter by grasping the handle t^5 , will push the rod in a direction opposite to that of the arrow near it in Fig. 14, and start the tacking operation, it being thereafter carried on automatically until the upper has been tacked all about, when the machine will be automatically stopped. The base plate d^7 and its parts to sustain the last are designated herein as the jack. The tack-

ing head constitutes one form of tacking means for uniting the lasted upper to the inner sole, but this invention is not limited to the exact shape and construction of the parts so far described, and instead of them I may use any equivalent or well known devices, the gist of this invention lying in means to support or carry a plurality of jacks, means to hold the uppers pressed against the lasts mounted on said jacks and means to secure the lasted upper to the inner sole the said lasting devices and upper securing means being separated one from the other so that one of said jacks with a shoe on its last may be presented to the lasting devices and then to the means for securing the upper to the inner sole, thus enabling these operations to be carried on simultaneously.

In operation the nose of the tacker head has imparted to it, by the levers with which it is connected, peculiar motions during the insertion of each tack, that is, the head is lowered at the outer side of the edges of the upper, and the nose meets the clamps and slides across the same onto the overturned edge of the upper to tack it to the inner sole, and then the tacker head is lifted from the upper and is carried upwardly and backwardly into its inoperative position, after which latter movement the necessary change of relative position of the head and jack are made preparatory to driving a second tack, and then the head is again moved over onto the upper as before. In this way the tacker head has given to it four motions. When the last is being changed on a jack and the shoe is being prepared for lasting, the ratchet wheel g is held stationary by a pin w^2 at the end of an elbow lever w^{13} , pivoted on an ear of the carrier g^2 . A suitable detent w^3 acts to engage the teeth of the wheel to prevent it from being rotated in the wrong direction. The hopper b^7 has attached to it an extension chute c^{20} and tacks which drop onto the inclined bottom of the hopper slide off therefrom into the chute and enter the receptacle c' .

Having described my invention, what I claim as new and desire to secure by Letters Patent of the United States is:—

1. In a machine of the class described, the combination of a movable carrier, a plurality of jacks and upper clamping devices mounted thereon, means to rotate said jacks on said carrier, heel and toe lasting devices supported independently of said carrier and adapted to coöperate in succession with said jacks to last the shoes on the lasts mounted in said jacks, means to secure the lasted uppers to the inner soles held on the bottoms of the lasts supported on said jacks, said carrier being revoluble to present said jacks and the shoes carried thereby successively to said lasting devices and then to

- the said upper securing means, and means to actuate said upper securing means automatically to connect said lasted upper to said inner sole, substantially as described.
5. 2. In a lasting machine, a plurality of shoe supports, end lasting means, operating means therefor, fastening means, means to impart to it in-and-out and traveling movements, a carrier for said supports, and means 10 to rotate automatically only that one of said supports which occupies a position with relation to the fastening means to have the upper of the shoe held by it secured to the inner sole.
15. 3. In a lasting machine, tacking means, lasting means comprising levers sustaining at their upper ends slides adapted to be moved over respectively the toe and heel ends of the last and to be closed in such position, and a carrier having a plurality of jack sustaining means for clamping the upper of a shoe to the sides and heel and toe of the last, said carrier being revoluble to place one or the other of the jacks in operative position under the lasting means, and means operating to partially rotate each of said jacks while tacks are being driven to last the uppers about the heel and toe ends of a shoe.
25. 4. A machine of the class described having, in combination, lasting devices, a single automatic fastening means, a plurality of rotatable shoe supports, movable means adapted to sustain said shoe supports and 30 present the same successively first to said lasting devices and then to said automatic fastening means for securing the lasted material in position, and means for rotating automatically said shoe supports when in 35 position to receive fastenings.
40. 5. A machine of the class described having, in combination, end lasting devices, a single automatic fastening means, a plurality of rotatable shoe supports, movable means adapted to sustain and present the 45 supports successively to said end lasting devices and then to said automatic fastening means, and clamping means to clamp the lasted material to the last while each shoe 50 support is being moved from the end lasting devices into position to have fastenings driven into the material carried by the shoe support.
55. 6. In a lasting machine, a plurality of jacks, lasting means to lay the edge of the upper over the bottom of a jack supported last, automatic fastening means, and means to sustain said jacks that they may move successively from the lasting means into position to enable said fastening means to 60 drive fastenings in the upper previously acted upon by the lasting means.
65. 7. In the lasting machine, a plurality of jacks, lasting means to lay the edge of the upper over the bottom of a jack supported
- last, automatic fastening means, and means to sustain said jacks that they may be moved from the lasting means into position to enable said fastening means to drive fastenings in the upper previously acted upon by 70 the lasting means, and means co-acting with each of said jacks to retain the upper in contact with the sides of the last while the jack is moved from the position in which it was lasted into the position in which the 75 fastenings are inserted in the upper.
8. In a lasting machine, a plurality of jacks, lasting means to lay the edge of the upper over the bottom of one of the jack supported lasts, automatic fastening means, and means to sustain said jacks that they may be moved from the lasting means into position to enable said fastening means to drive fastenings in the upper previously 80 acted upon by the lasting means, and means to impart a traveling movement to the fastening means while inserting fastenings in the upper along the sides of the last.
85. 9. An organized machine comprising a rotatable table, two shoe supports thereon each of which is rotatable about its own axis, means for locking a shoe support against rotation in one position, lasting means to prepare the upper for tacking while the shoe occupies the locked position, a tacker, and means to unlock the support, said parts being arranged to permit the rotation of the support when the shoe has 90 been transferred by rotation of the table from the lasting means to the tacker.
10. An organized machine having, in combination, lasting means to form the toe and heel portions of an upper into position on the shoe bottom to be secured, fastening mechanism to secure the upper so formed, a shoe support to sustain the shoe for the 100 operation of the lasting means and movable away from said lasting means to transfer the shoe to the fastening mechanism.
11. An organized machine having, in combination, lasting means to form the toe and heel portions of an upper into position on the shoe bottom to be secured, fastening mechanism to secure the upper so formed, a shoe support to sustain the shoe for the 110 operation of the lasting means and movable away from said lasting means to transfer the shoe to the fastening mechanism, said support including means to hold the upper 115 conformed to the last about the edge of the shoe while the fastening mechanism is operating thereon.
12. An organized machine having, in combination, lasting means to form the toe and heel portions of an upper into position on the shoe bottom to be secured, fastening mechanism to secure the upper so formed, a support to sustain one shoe for the operation 120 of the lasting means, a second support to sustain another shoe for the operation of 125

the fastening mechanism, and a carrier by which each support may in turn be caused to transfer a shoe held in lasted position from the lasting means to the fastening mechanism.

13. A machine of the class described having, in combination, end lasting mechanism to operate on a shoe in one position, side lasting and fastening mechanism arranged to operate on the shoe when the shoe has been moved into a different position, and a

support to sustain the shoe for action by said mechanisms in turn and movable to present the shoe to the said mechanisms.

In testimony whereof, I have signed my ¹⁵ name to this specification, in the presence of two subscribing witnesses.

THOMAS K. KEITH.
